UNITED STATES PATENT OFFICE

1,983,028

OIL CRACKING APPARATUS

Ira Walton Henry, Greenwich, Conn., assignor
to Ionizing Corporation of America, New York,
N. Y., a corporation of New York

Original application May 6, 1929, Serial No.
360,926. Divided and this application March
20, 1930; Serial No. 437,557. Renewed April 24,
1934

12 Claims. (Cl. 204—31)

This invention relates mainly to improvements in oil cracking apparatus.

This application is a division of my application Serial No. 360,926, filed May 6, 1929, for Heat 5 treatment of petroleum oil vapor and other hydrocarbonaceous starting material; method and apparatus.

One object of my invention is more effectively to dissociate or ionize the petroleum oil, vapor 10 or other hydrocarbon starting material, such as crude petroleum, raw gasoline, or other petroleum oils or their vapors by passing them through an electromagnetic field in a new and hitherto unknown advantageous way, as described below, 15 for production of gasoline, or other products from a suitable starting material.

Another object of the invention is to improve present petroleum oil cracking operations by suddenly raising to a cracking temperature the oil 20 vapor or gases, after they have been preliminarily obtained by heat treatment, and while they are at a relatively high temperature of approximately 500° or 600° F. and before such pre-heated, hot, gaseous vapor is led into a heat interchanger, such as a condenser or other apparatus for reception of the cracked vapor.

By this feature of my invention the gaseous vapor is given a sudden increase in temperature while it is in its pre-heated condition and is 30 flowing to auxiliary apparatus.

It is well known that final cracking must be accomplished within temperatures that will not cause the gaseous vapors to carbonize; and my present invention suffices for obtainment of final 35 and complete cracking without carbonization, and thus pertains to one of the most critical steps in the cycle of production of light hydrocarbons, such as gasoline for example. I have discovered that the desired result, without carbonization, is obtainable by giving the pre-heated, vapor or oil 40 a sudden increase of approximately 200° F. or even higher temperature, a hot shock as it were, just before the vapor goes to a heat interchanger or the like; superheating the hot vapor to from 45 between 500° or 600° Fahrenheit up to approximately 800° F. depending on the quality of the oil to be cracked.

My apparatus herein set forth is useful in other connections than above indicated, and I do 50 not intend to limit my claims to its use only in the described manner but to claim it broadly for every use to which it can be put.

In the accompanying drawings forming a part hereof and illustrating my present invention in 55 different forms,—

Fig. 1 is a diagrammatic view of a cracking still provided with exterior heating means and having a discharge pipe communicating with my new superheater which discharges into a heat interchanger.

Fig. 2 is a lengthwise, central section and elevational view of one form of my new superheater embodying the invention, in communication with a pre-heated, hot gaseous vapor, supply pipe and also in communication with a pipe for discharging the superheated vapor into a desired apparatus for subsequent treatment; the superheater including a conduit having an enlarged portion forming an expansion chamber.

Fig. 3 is a lengthwise central section and elevational view of another form of the superheater illustrated in Fig. 1.

Fig. 4 is a lengthwise, central section and elevational view of another form of the apparatus illustrated in Fig. 1. This Fig. 4 form of the invention is the preferred and best form of the invention now known to me for all now contemplated uses of my invention. I will first describe the apparatus in its use as a preheater in which a pyrometer is employed.

In all the figures, a pyrometer is shown as a member of the superheater, the pyrometer having a heat sensitive element exposed to the action of a high frequency, oscillating electromagnetic, hot field, effecting apparatus and means for controlling the heat, the heat sensitive element of the pyrometer being inductively heated from the electromagnetic field.

Referring to the different forms of the invention illustrated in the drawings,—

In Fig. 1, B diagrammatically indicates any of the usual type of apparatus in which petroleum oil is vaporized by application of external heat. For illustration, apparatus B may be supposed to be a still provided with either side or bottom heating devices, as at B'. In such apparatus, long commonly used for crude oil vaporizing, a delivery pipe 2 leads to some kind of vapor treating apparatus such as B² which may be either a heat interchanger, condenser, expansion chamber, or otherwise. Heretofore, the hot vapors flowing through the pipe 2 have deposited a carbon content on the walls of the pipe and other walls with which they have come in contact, thus carbonizing the walls and also impairing the quality 105 of the distilled product by the presence of excess carbon in the distillate. In my opinion, based on my experience and work done in this connection, the result of subjecting the pre-heated vapors to the action of the high frequency, os- 110

5 cillating, electromagnetic field herein mentioned is to break up the carbon molecules in the vapor into exceedingly small electrified particles, and thus to involve ionization. At any rate, by my invention the deposit of carbon from the heated and cracked vapor in the pipe is practically prevented, the quality of the ultimate product, such as gasoline or the like, being materially improved. By my invention, I give the hot, pre-heated vapor or vapors, while flowing from the still, a sudden boost in temperature or hot shock as above described, and have discovered that by so doing carbonization of the pre-heated cracked oil vapors, during their discharge flow is, largely and 10 in some cases wholly, obviated. Indeed the sudden hot shock given to the hot vapor in its flow is a cracking step.

15 Fig. 2 shows a vapor or oil conduit A of electric current conducting material. Conduit A is tapped at 1 into the starting material or vapor supply pipe 2 and is extended into an elongated coil which terminates and discharges at 3 within an expansion chamber structure A' of dielectric material, such as ceramic, pyrex or the like or any other suitable material. The expansion chamber structure A' is shown annular in cross section and is in effect a cross sectionally enlarged extension of conduit A. It has a closed 20 end wall 4, preferably at its end nearest the take-off, at 1, of the starting material; is of an interior cross section substantially larger than that of conduit A in order to permit expansion of the vapor discharged into the expansion chamber from the conduit A at 3. An end of the expansion chamber, preferably furthest from the discharge at 3, is open and in communication with a discharge or delivery pipe 5 which conveys the superheated vapor to any desired apparatus, such as a heat interchanger, condenser or otherwise. The interior circular wall of expansion chamber A' has a lining 6 of some suitable refractory material, such, for example, as asbestos. The purpose of lining 6 is to support the edges of each of, preferably a series of transverse, vapor-baffling and passing means 7 shown as metal wire screens through the interspaces of which the superheated vapor may flow. In all forms of the invention, the lining 6 serves to diminish escape of the electromagnetic energy from the expansion chamber. The peripheral margin of such screens is anchored in the asbestos or other lining, out of contact with the wall of the expansion chamber structure A', as shown at 8, in order to prevent unequal heating of the metal screen or other equivalent vapor baffling and passing elements which also function as short circuited secondaries in the superheater, when the energizing current is on. A pyrometer having a heat sensitive element 9 is provided for the expansion chamber, and is located within the influence of an oscillating electromagnetic field established by an energizing, alternating, electric current within the expansion chamber, and within and exteriorly of the coiled portion of conduit A which is of copper or other suitable, alternating, electric current conducting material. The pyrometer includes an exteriorly observable heat degree indicator 10. The ends of expansion chamber structure A' are shown electrically insulated at 11 from the starting material supply pipe 2 and also from the discharge and delivery pipe 5. The coiled portion of conduit A is electrically connected at 12—12, spacedly apart, with the ends of an alternating electric current conductor 13—13, each leading from a brush 14 of

80 an alternating electric current dynamo 15. A condenser 16 is interposed in each conductor 13; and rheostat 16a is interposed in one of the conductors 13 in order to permit regulation of the heat induced in the short circuited secondaries, which form electric current resistances, from the electromagnetic field established in the expansion chamber when the current is on. The coiled portion of conduit A surrounds the expansion chamber structure A'. But it is better and safer to install such coiled portion of the starting material conduit A inside the expansion chamber and within the lining 6 as shown in Fig. 4.

85 The degree of heat generated in the expansion chamber, at any given moment, is determined electrically by regulation of the current, and is known instantly to an attendant by his observation of a corresponding pyrometer reading. This structure permits the apparatus to be used as a superheater or heat booster for giving pre-heated hydrocarbonaceous vapors, or other fluid starting material, supplied to conduit A from pipe 2 a sudden increase in temperature. The attendant can instantly raise or boost the temperature of the pre-heated starting material by regulation of the current, and by observation of the pyrometer reading give the material a sudden increase in temperature.

90 The short circuited, secondary forming screens 7 form electric resistances in the electromagnetic field and may be very highly heated, even to the melting point if it were so desired; but in use the temperature effected in the expansion chamber is to be varied, usually according to the quality and character of the starting material, as above 95 stated, the pre-heated vapors received from the supply pipe being usually of a temperature about 200° F. lower than that suddenly given them in the expansion chamber by regulated operation of the apparatus which forms a superheater if it is so 100 used as just described.

105 The short circuited, secondary forming screens 7 form electric resistances in the electromagnetic field and may be very highly heated, even to the melting point if it were so desired; but in use the temperature effected in the expansion chamber is to be varied, usually according to the quality and character of the starting material, as above 110 stated, the pre-heated vapors received from the supply pipe being usually of a temperature about 200° F. lower than that suddenly given them in the expansion chamber by regulated operation of the apparatus which forms a superheater if it is so 115 used as just described.

120 As the dynamo and high frequency, alternating current generating, distributing and heat control apparatus above described are shown and identified by corresponding reference numerals in remaining figures of the drawings, no further detailed description thereof will be given.

125 In Fig. 3, the expansion structure A' differs from that above described in that both its ends are closed except for its intake port 17 and discharge port 18. Starting material, such as any petroleum oil or vapor, for example, supplied to the expansion chamber will be vaporized if the starting material is oil; or further and more actively vaporized if the starting material is already a vapor, and will flow out through discharge port 18 into the partially coiled conduit A and be discharged therefrom at its discharge end 19. If desired, the starting material could be introduced into the expansion chamber through the discharge end 19, circulated through the coil, discharged expanding into the expansion chamber, and flow out through the intake port 18, involving a reversal of the initial supply and ultimate discharge. In all other respects this form of the invention is like that set forth in connection with the Fig. 2 form.

130 In Fig. 4 there are no short circuited, secondary forming elements, the screens being omitted. The coiled portion of conduit A is within the expansion chamber and its convolutions serve as gaseous vapor baffling and passing means. The coiled portion of the electric current conducting and starting material conduit, offering resistance to the high frequency, alternating current flowing through it and being in the high frequency, elec- 135 140 145 150

tromagnetic field which is generated when the energizing current is on, becomes heated and may be highly heated, and the starting material in the coil is subject to influence of the heat and of the high frequency oscillations of the electromagnetic field. In this form of the apparatus or superheater, the starting material is assumed to be taken into an outside portion of conduit A, as at 20; to flow through the interior coiled portion 10 of the conduit and to discharge at 21 into the expansion chamber from which the superheated vapor treated flows out through a discharge or delivery pipe 22.

In practice, I employ a frequency of between 15 and about 760 and 2,000 cycles per second as the particular character or quality of the hot, gaseous vapor to be superheated may require.

If desired, a catalyst may be located in the electromagnetic field. The screen 7, one or all 20 may be of catalytic metal.

Preferably the suddenly superheated and cracked vapor is suddenly chilled in the heat interchanger, and the apparatus shown is suitable for this important purpose and the constituents of 25 the finished product are fixed and stabilized by the sudden changes in temperature, the high temperatures being affected by induction from the hot, electromagnetic field.

I have found that gasoline cracked in a hot, high 30 frequency oscillating electromagnetic field contains a hitherto undiscovered and unrecognized waxy substance which is negligible in quantity but which indicates a new effect of the hot electromagnetic field and the action thereof, whatever 35 it may be on the petroleum oil vapor treated.

In the structure of Fig. 4, the high frequency, oscillating current in the turns of the coil re-acts on itself and heats the coil.

The foregoing description refers particularly, 40 apart from description of the differing forms of the invention, to use of the structure in suddenly raising the temperature of the starting material, whatever it is, whether an oil or a gas.

I will now set forth additional advantages and 45 features of the invention when used for production of gasoline or other products without preheating, but at any suitable temperature in the coil, screens or expansion chamber.

An important feature of the invention is the 50 location of the coil within the expansion chamber and its insulation from the side wall of chamber structure A' by the asbestos mat 6. Hereby the energy of the electromagnetic field is conserved to a very high degree for disintegration 55 action within the expansion chamber or still on the matter treated within it; and the more or less dangerous field oscillations or pulsations outside the still are so greatly reduced as greatly to increase safety to persons using the still or apparatus. This is one of the reasons why the Fig. 4 structure is the preferred structure.

I have pointed out above that a catalyst may be located in the electromagnetic field; that the screens 65 7 may be of catalytic metal; and that the screens as well as the convolutions of the coil on Fig. 4 act as baffles. It is a feature of this invention substantially to retard outflow of the treated material from the expansion chamber or still; that is, substantially to prolong the period of its 70 subjection to the electromagnetic field force, for thereby I have found that a greatly superior quality of either gasoline or other products may be produced—by what may be metaphorically called—cooking the vapor.

The Fig. 4 structure is also greatly preferable

to the other illustrated structures because it serves a double field treatment of the vapor or vaporizing oil. The material entrant into the intake end 20 of the coil supply pipe is first subjected to electromagnetic field action while within and flowing through the coil turns, as the field oscillations or pulsations are partly through the coil wall and the space or chamber enclosed by the wall. As the coil product—vapor—flows out of the coil, at 21, into the expansion chamber or space, the vapor discharged instantly expands, and in its flow to the discharge port or pipe 22, flows through the field oscillations or pulsations exterior to the coil turns, thus involving a double field treatment of the discharged product.

The different portions of this new structure may be made of any suitable material. The casting A' may be made of a ceramic material if desired; insulating material other than asbestos may be used for the lining 6; the coil may be made of copper, or whenever desired, of a suitable catalytic metal, of which catalytic metal the screens 7 are preferably made. The screens 7 are spaced apart for more effective retardation of vapor escape. The screens are baffle plates. The coil 100 turns in Fig. 4 are baffling elements and may be catalysts. Screens 7 may be inserted in the expansion chamber of casing A', if desired, as will be obvious from the drawings. In such case, they would form short circuited secondaries.

I will now set forth new and formerly unexpected effects obtained from use of this invention, wholly apart from its first described use as a mere superheater.

What I claim is:

1. The combination with a crude oil vaporizing still including still heating means and a discharge pipe; and a heat interchanger in conduit communication with said discharge pipe; of a superheater conduit in intermediate communication with said discharge pipe and with the intake of said heat interchanger; means for heating the superheater conduit inductively from a high frequency, oscillating electromagnetic field; and means for establishing a high frequency, oscillating electromagnetic field within and adjacent the superheater conduit; the latter means including a heat regulating device; said means for heating the super-heater conduit inductively including a high frequency, oscillating, hollow electric-current-conducting coil having an intake for oil vapor to be treated and a discharge for vapor treated, all arranged and operating for suddenly increasing the temperature in the superheater conduit at the will of the operator.

2. In apparatus of the class described, the combination of an expansion chamber structure; an electromagnetic field generating hollow coil; said expansion chamber being positioned within the generated electro-magnetic field; an insulating lining for the chamber wall between it and the coil turns; and current generating and current control apparatus in circuit with the coil; the wall of the expansion chamber being connectible with a supply pipe and also with a discharge pipe; the supply pipe communicating with the coil space for flow of material from the supply pipe through the coil.

3. In the combination set forth in claim 2, a series of spaced apart baffling members insulatedly mounted transversely of said chamber and of the coil axis.

4. In the combination set forth in claim 2, a baffling member; the coil discharging into the expansion chamber at a place remote from the dis-

charge port thereto to cause the expanded vapor issuing from the coil to pass the baffle and the electromagnetic field and to be retarded in its outflow by the baffle.

5. In apparatus of the class described, the combination with electric current generating and control apparatus; of a hollow electric current conducting coil in circuit with said apparatus; and an expansion chamber structure into the chamber of which the coil discharges said expansion chamber being positioned within the generated electric field of said electric current-conducting coil; the coil having an intake end for supply of material to be treated.
10. 6. In apparatus of the class described, the combination of oil cracking apparatus and a heat interchanger with an intermediate conduit forming apparatus in communication with both the oil cracking apparatus and the heat interchanger; said intermediate apparatus including an electric current conducting and electromagnetic field generating hollow coil serving also as a conduit between the cracking apparatus and the interchanger; the coil being provided with a walled expansion space; and an electric current generating, electromagnetic field inducing, frequency regulating and current control apparatus with which the coil is in circuit said expansion chamber being positioned within the induced electromagnetic field of said electric current-conducting hollow coil.
15. 7. In the combination set forth in claim 6, the coil being exteriorly insulated.

35

80

8. In the combination set forth in claim 6, the expansion space having a conduit wall enclosing it; the coil being in said space and insulated from said wall.

9. In the combination set forth in claim 6, said hollow coil being insulatedly mounted within a chambered expansion chamber structure, in communication with the supply pipe and discharging into the expansion chamber remotely from the intake end of the coil and from the discharge port of the expansion chamber whereby the material flowing through the coil is acted on while flowing; expanded on its discharge, and then passes through the electromagnetic field exteriorly of the coil into the conduit leading to the heat interchanger.

10. In the combination set forth in claim 6, vapor escape retarding means within the expansion space.

11. In the combination set forth in claim 6, vapor escape retarding elements of catalytic metal.

12. The combination with oil cracking apparatus and heat interchanging apparatus; of an intermediate vapor treating conduit apparatus which is provided with a walled expansion chamber; an electric current conducting coil insulatedly mounted in the expansion chamber and serving as a conduit for material treated.
